(57) **CLAIM**

The ornamental design for a light panel, as shown and described.

DESCRIPTION

FIG. 1 is a perspective view of a light panel according to the new design.

FIG. 2 is a front view of the light panel of FIG. 1;

FIG. 3 is a rear view of the light panel of FIG. 1;

FIG. 4 is a right-side view of the light panel of FIG. 1;

FIG. 5 is a left-side view of the light panel of FIG. 1;

FIG. 6 is a top view of the light panel of FIG. 1; and,

FIG. 7 is a bottom view of the light panel of FIG. 1.

The broken lines shown in the drawings illustrate portions of the light panel that form no part of the claimed design.

1 Claim, 7 Drawing Sheets
